UNITED STATES PATENT OFFICE.

JEROME B. JACOBSON, OF NEW YORK, N. Y.

GAME DEVICE.

Application filed June 13, 1927. Serial No. 198,640.

This invention relates to game devices and in particular to one embodying a competitive feature.

A particular object of the invention is to provide a game somewhat similar to football which can be played by opposing players to project a ball through a barrier of opposing paddles into the opposite goal post or receptacle.

10 A still further object of the invention is to provide a plurality of opposing paddle members which are so arranged that the operation of a ball directly by one of them will result in its striking the opposite paddle, 15 the game board being so arranged that skill is required in the manipulation of the paddles at a predetermined time in order to project the ball across the field.

A still further object of the invention is 20 to provide a game board having a plurality of depressions whose lowest point is adjacent each paddle whereby the ball will always roll either in front of or behind one of the operating paddles so that it need not be touched by 25 the hand of the player.

To enable others skilled in the art to fully comprehend the underlying features of my invention that they may embody the same in the various modifications in structure and 30 relation contemplated, a drawing depicting a preferred form has been annexed as a part of this disclosure and in such drawing, similar reference characters denote corresponding parts throughout all the views, of which,

35 Figure 1 is a view in perspective of my improved game device, one corner thereof being broken away to disclose the interior construction of the paddle operating members.

Figure 2 is a top plan view of the game 40 board, the depressions therein being shown and also the position of the paddles and the ball during play, a corner of the device being broken away to illustrate the link mechanism which is used to manipulate the paddle.

45 Figure 3 is an enlarged, longitudinal section taken on the line 3—3 of Figure 2 and shows the relative location of the paddles and the mode of operating the same, more particularly the board formation is shown which 50 pockets the ball in position to be projected by the paddle, and

Figure 4 is a cross section view taken on the line 4—4 of Figure 2 showing the construction of my game device.

55 Referring to the drawings in detail 5 indicates the side members and 6 the end members

of the game holding frame or receptacle which is provided adjacent the end 6 with an upstanding partition 7 which bounds the end of the game board or field 8. If it is preferable in the construction of this game to have an outside frame piece of wood and then position therein through the medium of suitable spacing blocks 9 or edge members, a stamped out field or game board 8, so that 60 in one operation, the sides 7 of the game board may be provided having upstanding ends 10 which are opened at the central portion of each end of the field as at 11 to provide goal openings through which the ball 65 may be ejected to its seat in the receptacle formed between the ends 7 of the game board and the end wall 6 of the frame. By making the game board 8 out of metal, the same can be pressed and bent as at 12 to provide for 70 the ball holding pockets in the bottom of which are disposed the projecting paddles to be hereinafter described. These depressions 12 cause the ball to always be positioned before or behind the paddles and the ridges between the depressions 12 which are referred to as at 13 are sharp enough to prevent the ball from coming to rest thereon and consequently the ball in play will always be adjacent one of the paddles and in position to be 75 projected by the manipulation thereof.

It will be noted that adjacent the openings 11 through which the ball is rolled, the game board 8 is sloped slightly upward as at 13 so that it is more or less difficult to get 80 the ball into the goal and it must be projected thereinto with considerable force. In play, the ball is thrown any place upon the field and will come to rest in one of the depressions 12 and before one of the paddles. Then, in 85 order to project the ball back and forth in a competitive game, I have provided a plurality of transversely extending rocker rods 15 provided with upwardly disposed extensions 16, the extensions passing through openings 17 in 90 the bottom of the depression 12 and having secured in any suitable manner to their upper ends, the paddles 18. The rocker rods 15 are pivoted in the sides of the game board and are adapted to be rocked through the medium 95 of two longitudinally extending rods 18^a, the same being operated from the diagonally opposite corners of the game board so that the paddles operated thereby will work in a direction to project the ball back and forth 100 between them over the game board. The rods 18^a are pivoted as at 19 in any suitable man-

ner to alternate transverse bars 15 so that the manipulating member at one corner of the game board and indicated by the numeral 20 will operate the first two bars 15 at one side 5 of the board and on the opposite sides of the center line of the board 21 will operate also, the first two bars 15 so that sets of paddles carried by the first two bars will oppose the sets carried by the next two bars throughout 10 the length of the board, thus giving an opposing action and one through the medium of which the ball may be projected back and forth in competitive play.

The rods 18^a are connected to one end of 15 the board through the medium of the springs 22 which normally tend to keep the paddles in their forward position so that the same may be drawn back and snapped by the spring to project a ball. The opposite ends of the 20 rods 18^a or operating ends are connected to a link 23 through the medium of a bell crank 24, the link being connected pivotally to a manipulating lever 25 to the upper end of which is secured a finger piece or knob 26, 25 these operating mechanisms are disposed at the diagonally opposite corners of the board so that they can be conveniently manipulated by the thumb of the right hand of the player and the ball can be deftly struck back and 30 forth across the board by manipulation of the paddles 18.

As shown in Figure 2, the ball 26 is resting behind one of the paddles 18 and before the player controlling that particular paddle 35 could project the ball, it would be necessary for him to draw the paddle 18 back by manipulation of his finger knob 26 until the ball rolled around in front of the paddle at which time it could be projected and if it were not 40 projected properly, would strike the opposing paddle 18 and the player manipulating said last mentioned paddle could have the opportunity to project the ball toward the opposing player's goal.

It is quite evident that through the medium 45 of my construction, an exciting, active and competitive game can take place and sides can be formed for the complete playing of a football or other game and points may be scored.

It is also evident, that the handle knob car-

rying lever 25 may be suitably pivoted in the bottom 9 of the game device between the ends 6 and the game board end walls 7, it being of course understood, that the corner of the end 55 walls 6 may be cut away adjacent the manipulating lever 25 so that convenient operation thereof may take place.

It is evident, therefore, that I have provided a game device in which a ball may be 60 used and may be projected back and forth by players until it is finally lodged in one of the goals of either of the players and also one in which points may be scored during the 65 playing of the game.

It is also evident that I have provided a game device which may be made of few parts and one in which the ball need not be touched by the players during the manipulation thereof to completely play the game. 70

No rules are made up for the playing of the game as these may be promulgated to suit the needs of the players.

While I have illustrated and described my invention with some degree of particularity, 75 I realize that in practice various alterations therein may be made. I therefore reserve the right and privilege of changing the form of the details of construction or otherwise altering the arrangement of the correlated parts 80 without departing from the spirit of the invention or the scope of the appended claim.

Having thus described my invention, what I claim as new and desire to secure by United States Letters Patent is:—

A game device comprising a board having openings therein, depressions formed about said openings, transversely disposed cross bars beneath said board, paddles carried by the cross bars and extending through each of 90 said openings, said paddles being grouped in opposing sets at opposite sides of the game board center to oppose movement of a game piece, operating rods connecting the paddle carrying bars, means for normally urging the 95 rods in opposite direction, a lever at each end of the game board for operating said rods, and a partition at each end of the board behind which the lever is disposed.

In testimony whereof I affix my signature.

JEROME B. JACOBSON. [L.S.]
